UNITED STATES PATENT OFFICE.

EDWARD W. DAYKIN, OF YOUNGSTOWN, OHIO, ASSIGNOR, BY MESNE ASSIGNMENTS, TO TRUSCON STEEL COMPANY, OF YOUNGSTOWN, OHIO, A CORPORATION OF MICHIGAN.

STRIPPER FOR SLITTING MACHINES.

Application filed January 23, 1925. Serial No. 4,296.

This invention relates to machines for cutting or slitting metal sheets used for making expanded metal, and more particularly to a novel support and assembly for the stripper blades which insure the proper removal of the slitted blank from the cutting discs and properly guide it out of the cutting machine.

A primary object of the invention is to provide a novel mounting for the individual stripper blades, whereby all of the blades for a particular cutting roll may be put in place as a unit and removed in the same manner, thus saving considerable time when the strippers are being removed or inserted, and also facilitating their adjustment into proper alinement. Heretofore it has been customary to mount the strippers on a fixed pin, with the result that the mounting is accompanied by a certain amount of looseness, and even though in some cases the strippers may be mounted initially with considerable rigidity, they in time acquire a looseness which cannot be tightened except by shutting down the machine and re-aligning the whole set by some method of redressing all of the parts.

Accordingly, the present invention has in view a novel mounting for the series of individual stripper blades which fit between the cutting discs, whereby all of the strippers may be rigidly locked in the desired set position, and even though looseness or play develops in use, such play may be readily removed by a simple and practical form of adjustment without requiring the removal of any of the strippers, and without requiring the taking down of any part of the apparatus or otherwise temporarily rendering it inoperative and out of use.

A further object of the invention is to provide a simple, practical, and substantial construction that is easily made and assembled and readily manipulated at all times thereby insuring the full period of operation for the cutting machine and consequently increasing its production, while at the same time also performing better stripping and producing less scrap.

With the above and other objects in view which will more readily appear as the nature of the invention is better understood, the same consists in the novel construction, com-

bination and arrangement of parts herein-after more fully described, illustrated and claimed.

A preferred and practical embodiment of the invention is shown in the accompanying drawings in which:

Figure 1 is a vertical sectional view taken through a pair of cutting rolls of a slitting machine of the Curtis type, illustrating the application of the invention.

Figure 2 is a horizontal sectional view taken on the line 2—2 of Figure 1.

Figure 3 is an enlarged detail horizontal sectional view of one corner of the improved supporting and adjusting means for the strippers.

Similar reference characters designate corresponding parts throughout the several figures of the drawings.

The stripper blades or fingers which fit between the steel slitting discs are made of tempered steel and are accurately formed so that each one of the whole series are duplicates of the others and no reason has been found to exist whereby one stripper will become differently worn than the others of the same set. Therefore, it is one of the primary objects of the present invention to adjust all of the strippers as a unit thereby permitting of readily taking up any slack or looseness which develops in the strippers due to the wear, without the necessity of shutting down the machine and re-aligning the whole set of strippers by redressing or re-machining the same.

The said stripper blades are designated generally as S, and having a relatively tight frictional fit between the cutting discs C of the cutting rolls R which may be mounted in the conventional manner in the frame F, and rotate in the direction of the arrows shown in Figure 1. The sheet metal to be slit is fed between the rolls R—R and the strippers S are preferably employed in upper and lower units as shown in Figure 1 with the extremities which project between the cutting disks rounded to thereby form a guide for facilitating the entry of the sheet to be slit between the rolls. The strippers of the upper and lower units have their adjacent stripping edge portions properly spaced apart to permit of the passage of the

slotted sheet therebetween as the cutting rolls slit and feed the sheet through the slitting or cutting machine, and each stripper includes the sheet finger portions which project between the cutters of the rolls, as indicated, and the supporting end portions a having the apertures or openings a' and the opposite spaced abutment shoulders a'' .

According to the present invention the 10 said supporting ends of the strippers are all mounted on a common assembly bolt 1, and alternate with fillers or spacers b for properly spacing the strippers with reference to the cutting discs. As shown in Figs. 2 and 3, the 15 said assembly bolt is preferably threaded at opposite ends thereby to receive the clamping nuts 2, and also the said ends are mounted in slidable or shiftable adjusting plates 3.

The plates 3 are important since they provide in effect a carriage for the bolt, and, according to the embodiment shown may be of angular formation thereby to fit around the opposite ends of the bed or carrier block 4 to which they are slidably connected by 25 means of the screws 5 and slots 6 shown in Figure 3. For the purpose of accommodating the bolt 1 and the supporting ends of the strippers a , the said carrier block 4 is grooved or recessed as indicated at 7 thereby 30 to house and accommodate the rounded supporting ends of the strippers.

When the strippers and the filler pieces are all assembled on the bolt 1 and the latter is in turn supported in the adjusting plates 35 3 it will be apparent that the rounded supporting ends of the strippers S will lie within the recess 7 of the bed block while the shoulders a'' have an abutting engagement with the edge portions of the bed block adjacent the recess 7 thereby preventing relative rotary movement of the strippers on the bolt and holding all of the same in rigid alignment and position.

To insure the correct positioning and alignment of the strippers as above indicated and to also take up wear thereon, the angular flange or wing portions 8 of the adjusting plates 3 are provided with adjusting screws 9 which work against the rear face of 50 the bed block 4 and have a threaded feed-engagement with the rear flange portions 8 of the adjusting plates. By turning the adjusting screw 9 it will be apparent that the plates 3 may be drawn rearwardly thereby 55 to pull the bolt 1 backwardly and force the shoulders a'' of the strippers firmly against the edges of the bed block adjacent the recess 7. Thus when looseness in the strippers occurs it is only necessary to give the screw 60 9 the requisite number of turns to pull the bolt backwardly as a unit and force all of the strippers against the recessed face of the bed block as indicated.

The said bed blocks 4 are preferably 65 mounted upon the rest bars 10 or equivalent

part of the frame F, and may be readily secured in proper position by machine screws 11 or the like.

The construction described provides a self-contained removable stripper carrying unit, the same carrying all of the stripper members for each roll in such a way that all the strippers in each unit may be simultaneously adjusted without the necessity of taking down the machine or otherwise interfering with its operation. When it does become necessary to remove the strippers, the entire assembly may be removed as a unit by simply unlocking or releasing the bed block 4 from the rest bar 10 by removing the screws 11. The entire unit can then be withdrawn from the machine and then reinserted after it has been repaired, or a new duplicate unit may be quickly inserted without difficulty or delay.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

1. A stripper blade mounting for slitting machines including stripper blades having shoulders a carrier block removably mounted in the machine, and adjustable means for abutting the shoulders of the stripper blades into rigid engagement with the carrier block.

2. A stripper blade mounting for slitting machines including a carrier block removably mounted in the machine, a bolt having the stripper blades assembled thereon, shiftable plate members slidably mounted on the carrier block and supporting said bolt, and means for adjusting said plate members.

3. A stripper blade mounting for slitting machines including a carrier block removably mounted in the machine, said block having a recess, a member having the stripper blades assembled thereon and lying within said recess, means at the end of the recess of the carrier block for shiftably supporting said member, and means for adjusting and setting said last named means.

4. A stripper blade mounting for slitting machines including a carrier block having a recess opening at one side thereof, a member having the stripper blades assembled thereon and lying substantially within said recess, plate members adjustably fitted to the ends of said carrier block, clamping means on the end of said member for engaging the outer faces of said plates, and means for adjusting said plates to move the said member transversely of the carrier block.

5. A stripper blade mounting for slitting machines including in combination with the

stripper blades having an apertured supporting portion and opposite shoulders, a carrier block having a recess, and a member fitting in the apertured portions of said 5 stripper blades and adjustably connected with the carrier block whereby said shoulders of the blades may be wedged into engagement with the block.

6. A stripper blade mounting for slitting 10 machines including in combination with the stripper blades having an apertured supporting portion and abutment shoulders, a recessed carrier block, a bolt adapted to receive the apertured portions of the stripper 15 blades and maintain the same in said recess whereby the shoulders engage with the edges of the carrier block adjacent the recess, plates slidably mounted on the carrier block and supporting the carrier bolt, and means 20 for adjusting and setting the plates in the desired adjusted position.

7. A stripper blade mounting for slitting 25 machines including a carrier block removably mounted in the machine, said block having a recess opening at one side thereof,

a bolt having the stripper blades assembled thereon and lying substantially within said recess, adjusting plates located at the ends of said carrier block and receiving the ends of said bolt, said plates being provided with 30 guide slots, guide projections on the carrier block and engaging in said guide slots of the plate members, an offset portion on the plate members, and an adjusting screw carried by said offset portion and engaging with 35 the carrier block.

8. A stripper blade mounting for slitting 40 machines comprising in combination with the stripper blades having wear shoulders, a carrier block, means for carrying said blades and taking up wear on said shoulders, and means for moving said first mentioned means at right angles to the wear edges of said shoulders to cause said stripper blades to rigidly engage with the carrier 45 block.

In testimony whereof I hereunto affix my signature,

EDWARD W. DAYKIN.
